(57) CLAIM

I claim the ornamental design for the clothing, wig, and hair extensions travel and storage bag, as shown and described.

DESCRIPTION

FIG. 1 is a front, top, and left perspective view of the clothing, wig, and hair extensions travel and storage bag on a hanger;

FIG. 2 is front elevational view of the clothing, wig, and hair extensions travel and storage bag on the hanger;

FIG. 3 is a rear elevational view of the clothing, wig, and hair extensions travel and storage bag on the hanger;

FIG. 4 is a left side elevational view of the clothing and extension wig bag on the hanger;

FIG. 5 is a right side elevational view of the clothing, wig, and hair extensions travel and storage bag on the hanger;

FIG. 6 is a top plan view of the clothing, wig, and hair extensions travel and storage bag on the hanger; and,

FIG. 7 is a bottom plan view of the clothing, wig, and hair extensions travel and storage bag on the hanger.

The broken line hanger represents environment. The remaining broken lines illustrate portions of the clothing, wig, and hair extensions travel and storage bag. None of the broken lines form part of the claimed design.
